PHONOGRAPH TURNTABLE ASSEMBLY
Frederick H. Drake, Boonton, N.J.
(Squire Road, Roxbury, Conn.)
Filed July 7, 1958, Ser. No. 747,093
6 Claims. (Cl. 274—39)

The invention relates to phonograph turntable assemblies and more particularly to supporting structures for isolating the record table and pick-up arm from spurious vibrations which would impair sound reproduction from the record. This is a continuation-in-part application of my co-pending application, Serial No. 678,818, filed August 19, 1957 now abandoned.

It is the present practice in the best phonograph turntable assemblies to mount the record turntable, the driving motor for the turntable, and the pick-up arm on the same mounting board or cabinet. Such assemblies employ a massive table which is usually belt driven to minimize the transmission of vibrations from the driving motor to the table and record; and to minimize the transmission of motor vibrations to the mounting board, mechanical vibration filters are usually interposed between the motor and the mounting board. However, in spite of these and other precautions some spurious vibrations from the motor and from other sources are always present in the mounting board of even the best turntable assemblies in service use and reach the record table and pick-up arm, thereby interfering with the true sound reproduction from the record. The resultant spurious frequencies, or "rumble" as they are called in the art, are predominantly in the mid-bass to the sub-bass frequency region and although they may not always be heard directly by the human ear they tend to "muddy" the reproduction of the desired sound and, hence, impair the listener's enjoyment and increase listening fatigue.

Various proposals have been made to correct this condition. One approach has been to incorporate an electric "rumble" filter in the amplifying system. While such filters do reduce the "rumble" they are objectionable in that they reduce the desired low frequency reproduction from the record as well. Another suggestion has been to mount the pick-up arm somewhere other than on the mounting board but this solution has the drawback of destroying the unitary structure of the turntable assembly—a very important consideration as this assembly is widely sold as a unitary component of a record playing system.

It is an object of my invention to provide a supporting structure for the pick-up arm, or for the pick-up arm and the record table, that will isolate either the pick-up arm or both the pick-up arm and the record table from these spurious frequencies which would otherwise impair the sound reproduction from the record. A further object of my invention is to provide such a supporting structure which may be incorporated in the mounting board and sold therewith as a single unit. Still another object of my invention is to provide such a supporting structure capable of accepting standard commercial pick-up arms of various types and lengths without impairing the tracking ability of the arms. Another object of my invention is to eliminate all mass in the record table in excess of that required for stable rotational speed.

Briefly and generally, my invention comprises a turntable assembly in which the supporting structure for the pick-up arm, or for the record table and the pick-up arm, is inertially stabilized against frequencies in the audio range. This is accomplished by so constructing and mounting the supporting structure on the mounting board that the natural frequency of vibration of the supporting structure, including the pick-up arm, or the pick-up arm and record table, is in all directions well below the audio frequency range. Preferably, this is accomplished by

2

suspending the supporting structure from the mounting board through suitable means having compliance properly related to the mass of the supporting structure and accessories.

5 In one preferred form of the invention shown and described herein, the supporting structure comprises a platform for the pick-up arm mounted substantially in the plane of the mounting board and positioned within an opening therein with clearance all around. Depending from this platform and rigidly secured thereto is a weighted member having a mass many times greater than that of the pick-up arm. This member, in turn, is resiliently connected to the mounting board by means of a plurality of springs which support the weight of the supporting structure and which are positioned so as to maintain the supporting structure in a definite position of rest. Additionally, a rigid safety bracket is provided on the underside of the mounting board and passed underneath the supporting structure in order to limit the motion of the structure if an abnormally large downward force should accidentally be applied. A suitable pad is interposed between this rigid bracket and the weighted member so as to act as a damping means and protective cushion for the weighted member.

10 In another preferred form of the invention, shown and described herein, the supporting structure depending from the pick-up arm platform is made substantially larger and is extended so as to lie underneath the shaft for the record table. The supporting structure comprises a framework, which may advantageously be made in the form of a cross and may, at its center, carry the bearing housing for the shaft of the record turntable. As in the embodiment previously described above, the platform for the pick-up arm is mounted substantially in the plane of the mounting board and positioned within an opening therein with clearance all around. Similarly, the platform is rigidly connected to the framework and the framework is suspended from the mounting board by a plurality of springs. The bearing housing for the record turntable shaft extends 15 upwardly through an opening in the mounting board with clearance all around, thus, the springs support both the record turntable and the platform for the pick-up arm in suitable relationship with the mounting board. By this construction the weight of the turntable serves not only to stabilize rotational speed but to inertially stabilize the platform for the pick-up arm as well, thus obviating the need for any additional weighted member. Means for adjusting the amount of spring force adjacent the platform of the pick-up arm is provided so that the platform 20 may be leveled for various weights and lengths of the pick-up arms which may be utilized in the assembly.

25 It will be understood that the foregoing general description and the following detailed description as well are exemplary and explanatory of the invention but are not 30 restrictive thereof.

Of the drawings:

35 FIG. 1 is a top plan view of a phonograph turntable assembly constructed in accordance with the teaching of the present invention;

40 FIG. 2 is a side elevational view, partly in section, taken along the line 2—2 in FIG. 1 looking in the direction of the arrows;

45 FIG. 3 is a sectional view taken along the line 3—3 of FIG. 1 looking in the direction of the arrows;

50 FIG. 4 is a perspective view showing how the supporting structure is mounted within the opening in the mounting board;

55 FIG. 5 is a top plan view of another phonograph turntable assembly constructed in accordance with the teachings of the present invention;

60 FIG. 6 is a bottom plan view of the embodiment shown in FIG. 5;

FIG. 7 is a sectional view taken along the line 7-7 in FIG. 5 looking in the direction of the arrows;

FIG. 8 is an enlarged sectional view taken along the line 8-8 in FIG. 6 looking in the direction of the arrows;

FIG. 9 is a sectional view taken along the line 9-9 in FIG. 6 looking in the direction of the arrows.

A detailed description of the invention will now be given with reference to the preferred embodiment of the invention shown in FIGS. 1-4. The phonograph turntable assembly comprises a mounting board 10, having legs 12, each of which is provided with a coiled spring 14 extending therebelow in order to provide a resileint mounting for the mounting board within the cabinet or other enclosure (not shown) of the phonograph system. Mounted on the board 10 is a rotatable turntable 16 having a vertically arranged shaft which rotates in a bearing housing 18 that extends through the mounting board 10. A driving motor 20 for the turntable 16 is generally mounted underneath the mounting board but the drive shaft 21 therefor extends upwardly through the mounting board and is provided with three pulleys 22, 24, 26 thereon. The power of the motor shaft 21 is transferred to the turntable 16 by means of an endless belt 28 that passes around the turntable and a pulley on the motor shaft.

Adjacent one corner of the mounting board 10 there is provided a generally rectangular opening 30 therein and it is within this opening that the supporting structure 32 for the pick-up arm 34 is located. As shown in the drawing, the supporting structure 32 for the pick-up arm comprises a platform 36 having a substantially rectangular configuration that enables it to fit in the corresponding opening 30 in the mounting board 10 yet with a definite clearance all around its periphery. Depending from the platform 36 and rigidly secured thereto by means of the posts 38 is a weighted member 40 whose mass is several times greater than the mass of the pick-up arm 34 and which is rectangular in shape. Four coiled springs 42 are connected to the weighted member 40 and to the underside of the mounting board. These serve to support the supporting structure 32 for the pick-up arm.

In order to keep the supporting structure centered in substantially the same position, the springs 42 are located so that they are splayed to a slight degree, that is, the upper portions 44 of the springs 42 are positioned outwardly of the lower portions 46 of the springs where they are connected onto the weighted member 40. Additionally, a rigid U-shaped bracket member 48 is secured to the underside of the mounting board 10 adjacent the opening 30 and passes underneath the weighted member 40 at some distance therefrom. Interposed between the bracket 48 and the weighted member 40 is a pad 50 made from suitable damping material which, together with the bracket, serves to limit the downward movement of the supporting structure and to serve as a damping means therefor.

The platform 36 for the pick-up arm is made large enough to accommodate pick-up arms of conventional commercial types and lengths as desired.

The weight of the member 40 and the compliance of the springs 42 are selected so that the natural frequency of the supporting structure in all directions is well below the lowest audible frequency, which is approximately 20 cycles per second. In this way the supporting structure 32 as a whole is inertially stabilized against any frequencies in the audio range. Should any frequencies above the natural frequency of the supporting structure reach the structure they will be effectively attenuated through the resistance of the mass of the weighted structure 32 to vibration at those frequencies. In addition to having a weight great enough to lower the natural frequency of the structure 32 below the audio range it is also necessary that the total weight of structure 32 be sufficiently greater than the weight of any pick-up arm mounted on the platform

36 so that the added weight of the arm will not objectionably tilt or lower the structure from its normal unloaded position; otherwise the positioning of the arm on the platform for correct overhang or underhang would become difficult and the tracking of the arm could be impaired.

While the preferred embodiment of the invention described above shows the platform 36 in the same plane as the mounting board 10, it is to be understood that the invention is not limited to such a co-planar arrangement of these elements.

Referring now to FIGS. 5-9 there is shown another preferred embodiment of the applicant's invention. In this form of the invention the phonograph turntable assembly comprises a mounting board 110 removably resting on a box frame 111. As in the embodiment described above, the driving motor 120 is generally mounted underneath the mounting board but the drive shaft 121 therefor extends upwardly through the mounting board and is provided with one or more pulleys. The driving motor is suspended from the board on rubber shocks 123 or other resilient means to minimize the transmission of sound from the motor which would be otherwise amplified by a rigid connection with the mounting board. An endless belt 128 transmits power to the turntable 116. Similarly, an opening 130 is provided in the mounting board 110 and a platform 136, of slightly smaller dimensions than the opening 130, is positioned therein with clearance all around. A pick-up arm 134 is mounted on the platform 136 but is of a different type and has a different length than the pick-up arm 34, accordingly, it is secured to the platform 136 at a different point. The weighted member is formed by a framework 140 which extends beneath the platform 136 for the pick-up arm 134 and the bearing housing 117 for the shaft of the record turntable 116. Preferably the framework 140 is formed in the shape of a cross although this particular configuration is not necessary. As shown, framework 140 is formed by three channel bars or braces 150, 152, 154. Two of the braces 150, 152 are disposed along the same longitudinal axis and are joined one above the other by the posts 156 thus forming, in effect, a strong and rigid truss. The upper brace 150 extends at one end to a point underneath the central portion of the platform 136 and at its opposite end to a point underneath the periphery of the record turntable 116. Interposed between the upper and lower braces 150, 152 is a cylindrical bushing 118 adapted to receive the bearing housing 117 for the record turntable shaft 115 extending downwardly through the opening 113 in the mounting board. Suitable nuts 119 are provided to clamp the bushing 118 firmly with respect to the braces 150, 152. The upper brace 150 is also rigidly secured to the cross brace 154. The bearing housing 117 is firmly locked in bushing 118 by set screw 190 so as to provide the desired positioning of the framework with respect to the mounting board.

The framework 140 is suspended from the mounting board 110 by means of four springs 142 secured to the braces 150, 154 and recessed in openings in the mounting board. At the end 158 a rigid removable connection 138 is provided between the brace 150 and the platform 136. Additionally, the brace 150 is provided with an extension rod 160 bent at slight angle with respect to the longitudinal axis of the brace and also downwardly with respect to the plane of the brace. At its outer end 162 the rod 160 is flattened and attached by a spring 164 to an adjustable screw and nut 166 secured on the mounting board 110, so as to provide adjustable tension on the framework at this point to compensate for variations in the weights and dimensions of the various pick-up arms which may be mounted on the platform. In order to stabilize the platform horizontally the brace 150 is provided with a spring-like finger 170 on which is mounted a felt pad 172 which bears very lightly against the under surface 75 of the mounting board 110. This arrangement provides

a very slight amount of damping between the framework 140 and the mounting board 110 to stabilize the framework from displacements caused by a non-uniform or distorted belt, or from a slight imbalance in the turntable itself, or from the handling of the pick-up arm at the start of the record.

The compliances and dispositions of the supporting springs are chosen so that, in combination with the weight of the turntable 116, the framework 140, and the platform 136, natural frequencies of vibration in the vertical and the horizontal planes of approximately five cycles per second or less are obtained. In conjunction with the slight damping of the felt pad 172 the arrangement provides almost perfect inertial stabilization of the pick-up arm and the record turntable. Consequently, vibrations in the mounting board do not "muddy" reproduction from the record. By utilizing a suitably compliant endless belt 128 between the motor and the turntable the latter may be effectively isolated from any motor vibrations which might otherwise be transmitted to the table from this source.

In order to facilitate transportation of the turntable assembly, means are provided conveniently to secure the framework 140 and motor 120 to the mounting board 110. A flange 180 strongly attached to the top of the turntable housing 117 may be tightened down firmly against the mounting board 110 by four wood screws (not shown). Rigidly attached to the motor 120 just below the mounting board are two metal brackets 182, each with two tapped holes 184 disposed to receive machine screws (not shown). These may conveniently be inserted and tightened so as to clamp the motor brackets firmly against the underside of the mounting board during transportation. Furthermore, dimensions can readily be chosen so that, while the housing 117 is clamped down for local transportation, the turntable weight will automatically be supported by suitable pads 186 on the mounting board 110 and not by the more delicate end thrust bearing 188 which bears the weight of the table in service use.

What is claimed is:

1. A phonograph turntable assembly including a mounting board with driving motor secured thereon, a record turntable driven by said motor through resilient means and otherwise isolated from physical contact with said motor, a bearing housing for said turntable, a platform adapted to receive a pick-up arm, second resilient means, and a rigid supporting structure, said bearing housing and platform being attached in rigidly fixed relationship on said supporting structure, said structure being coupled to said mounting board by said second resilient means, and the combined mass of turntable, bearing housing, structure and platform so proportioned to the resilient means that the combination can oscillate freely, in both vertical and horizontal directions, only at frequencies below the audio range.

5 2. A phonograph turntable assembly as set forth in claim 1, including adjustable means resiliently connected between said mounting board and said supporting structure and adapted to permit adjustable levelling of said supporting structure to compensate for different loadings of said platform.

10 3. A phonograph turntable assembly as set forth in claim 1, including auxiliary damping means connected between said supporting structure and said mounting board.

15 4. In a phonograph turntable assembly having a mounting frame with driving motor attached thereto, a turntable with bearing means coupled resiliently to said motor and otherwise isolated from physical contact with said motor, and a platform for mounting a pick-up arm, means for rendering said turntable and platform jointly insensitive to spurious vibrations in the mounting frame arising from motor unbalance and other sources, comprising a massive sub-chassis to which said turntable bearing and platform 20 are secured in rigidly fixed relationship, said sub-chassis being resiliently attached to the mounting frame so as to permit the sub-chassis, weighted by said turntable and platform, to have free oscillation frequencies, vertical and horizontal, only in the sub-sonic range, whereby a record 25 mounted on said turntable and said pick-up are mounted on said platform are concurrently and inertially stabilized.

20 5. A phonograph turntable assembly as set forth in claim 4 including an adjustable resilient coupling between said mounting frame and sub-chassis to permit levelling of the turntable and pick-up arm platform for different 25 platform loads.

25 30 6. A phonograph turntable assembly as set forth in claim 4 including means for exerting a slight damping, between said mounting frame and sub-chassis, of vertical and horizontal relative motions, so as to shorten the duration of any sub-sonic oscillation of the sub-chassis caused by shock and service use.
